UNITED STATES PATENT OFFICE.

ROBERT S. MENNIE, OF CHICAGO, ILLINOIS, ASSIGNOR TO FLANNERY BOLT COMPANY,
OF PITTSBURGH, PENNSYLVANIA, A CORPORATION OF PENNSYLVANIA.

STAYBOLT.

1,359,819.

Specification of Letters Patent. Patented Nov. 23, 1920.

Application filed February 5, 1916. Serial No. 76,333.

To all whom it may concern:

Be it known that I, ROBERT S. MENNIE, a subject of the King of England, residing at Chicago, in the county of Cook and State 5 of Illinois, have invented a certain new and useful Improvement in Staybolts, of which the following is a full, clear, concise, and exact description.

My invention relates to improvements in 10 stay bolts, particularly those used in locomotive boiler construction.

In such constructions there is a relative movement between the outside sheet and the inside sheet which are spaced only a few 15 inches apart in certain places. The stay bolts therefore must permit this relative movement in addition to preventing spreading of said sheets due to the pressure developed.

20 As heretofore constructed, such stay bolts as have gone into general commercial use, provide a ball and socket joint, the socket being formed in a sleeve which is screw-threaded into an opening in the sheet. The 25 sleeve is provided with a cap to prevent leakage of the water which fills the space between the sheets or of the steam above the water level.

The operation of drilling and tapping the 30 holes in the outside sheets is expensive, as is also the sleeve itself, and since the stay bolts are fairly close together, an unnecessarily large amount of material is removed to provide room for the sleeve between the 35 bolt and the walls of said opening.

One of the objects of the present invention is to form a socket in an opening just large enough to accommodate the bolt, whereby these larger openings are avoided.

40 Another object is to provide a construction wherein the screw-threading of the opening is dispensed with.

Another object is to provide a construction 45 wherein the head of the stay bolt is in- closed in a cap which is welded to the outer sheet, whereby a permanently tight joint is secured.

A further object is to provide a hollow stay bolt in conjunction with such a cap,

whereby the breakage of the bolt is indicated by the blowing of water or steam into the fire box.

Other objects and advantages will be apparent from the subsequent description of the various embodiments of the invention 55 illustrated herein.

Figure 1 is a sectional elevation of one form of hollow stay bolt construction.

Fig. 2 is a sectional view showing a modified form thereof.

The outer sheet 1 and the inner sheet 2 are spaced apart several inches in practice, the sheet 2 constituting the wall of the fire box and the outer sheet being accessible for renewals of the stay bolts, etc. The space 65 between the sheets is filled with water up to a certain level, under the usual pressure of about 200 pounds to the square inch. The stay bolt 3 is designed to resist this pressure and prevent the sheets 1 and 2 from moving apart. Said stay bolt passes through an opening 4 in the outer sheet, the outer part of which opening is flared to provide a socket, the other end passing through a screw-threaded opening 5 in the inner sheet. 75 The head of the stay bolt 6 is substantially spherical and the inner half thereof fits the corresponding socket, whereby considerable play is possible, leakage of the water through the outer sheet being obstructed to a certain 80 extent. The head has a square recess 7 therein which communicates through an intermediate conical recess 8 with a longitudinal opening 9 extending to the end of the bolt, providing a hollow construction. The re- 85 cess 7 may be of any non-circular outline, whereby a tool may be inserted to rotate the stay bolt and the screw-threaded end 10 may be screwed into the inner sheet 2 after which the projecting inner end is riveted to form 90 a head 11. Access may be had to said inner end since it projects into the fire box, but access cannot be had to the space between the sheets 1 and 2 because of the narrowness of the passageway. The head of the bolt is 95 covered by a cap 12 the butt-portion of which is welded to the sheet at 13, the welded joint passing entirely around the cap. This weld

is preferably accomplished by autogenous welding, using any one of the commercial methods.

It will be seen that considerable relative movement of either sheet 1 or 2 in its own plane is permitted without diminishing the effectiveness of the stay bolt. What little leakage of water does occur through the ball and socket joint does not result in loss of water since the water cannot escape from the passageway between the head of the bolt and the cap. To prevent said water from being forced through the hole 8 into the fire box, the outer end of said hole is sealed up by a plug of welded metal 14. If the stay bolt breaks, as frequently happens, a fine jet of water or steam is forced into the fire box and is readily noticed, particularly at the end of the run when the fire is being drawn. No leakage from the outer sheet occurs however, in view of the tightly sealed cap.

The indication of the break being plainly indicated, the cap may be chipped off readily and a new stay bolt substituted for the broken one and a new cap welded in place.

Under the old practice, in order to ascertain that the stay bolts were broken, it was necessary to unscrew a great number of caps and make an inspection of the heads of the bolts, such inspection being required by the U. S. Government at definite intervals. Hollow stay bolts of the rigid type were also introduced, but were objectionable owing to the lack of play, as with all rigid forms of stay bolts. With my improved construction, an indication of a broken bolt is readily given without removing the caps and what is also important, there is no leakage through said caps.

In Fig. 2 the cap 15 is somewhat flatter than in the first form illustrated, and the head of the bolt 16 is hemispherical.

It is obvious that certain features disclosed in connection with one figure may be employed in conjunction with features disclosed in the other figure and various forms of devices other than those disclosed or suggested herein may be devised, which fall within the spirit of the invention as defined by the scope of the appended claims.

What I claim as new and desire to secure by Letters Patent of the United States is:

1. The combination with an outer and inner sheet, of a stay bolt passing through aligned openings in said sheets and having an enlarged head which, with the walls of the adjacent opening, forms a flexible joint, and a cap inclosing said head and having its butt portion welded to said outer sheet, said stay bolt having a substantially central opening extending from the end opposite the head and terminating within said head but not opening through the latter.

2. A stay bolt provided with a longitudinal opening extending therethrough and having an enlarged head, a non-circular recess in said head, and a tapering seat interposed between said recess and said longitudinal opening adapted to receive a plug substantially as and for the purposes set forth.

3. The combination with an outer and inner sheet, of a stay bolt passing therethrough, said stay bolt being provided with a longitudinal opening and having an enlarged head, a non-circular recess in said head, a seat interposed between said recess and said longitudinal opening adapted to receive a plug, and a cap inclosing said head and having its butt portion welded to said outer sheet.

4. The combination with an outer and inner sheet, of a stay bolt passing therethrough, said stay bolt being provided with a longitudinal opening and having an enlarged head, a non-circular recess in said head communicating with said opening, a plug in said opening lying within the plane of said outer sheet and a cap inclosing said head.

5. A stay bolt having a longitudinal opening therethrough and having an enlarged head at the outer end, and a plug welded in said opening within said head whereby the outer end of said opening is closed and the inner end is unobstructed.

6. The combination with the adjacent double walls of a steam boiler, of a stay bolt passing through aligned openings in said walls, said bolt having an enlarged integral head with a spherical surface forming with the opening in the outer of the two walls, a ball and socket joint, the other end of said bolt being upset, whereby said walls are prevented from moving apart but are permitted relative movement in their own planes, a cap inclosing said head and welded to said outer wall, said bolt having a longitudinal opening extending from the upset end to said head but not opening into the space beneath said cap, whereby leakage of steam or water through said ball and socket joint into said space will not be indicated at the open end of said bolt, whereas breakage of the latter between said walls will be indicated at said open end.

7. The combination with an outer and inner sheet, of a stay bolt passing through aligned openings in said sheets and having a head which with the walls of the adjacent opening forms a flexible joint, and a cap inclosing said head and welded to said outer sheet, said stay bolt having an opening extending from the end opposite the head and terminating within said head.

8. In a staybolt construction, the combination with inner and outer boiler sheets,

of a staybolt secured to the inner sheet and connected with the outer sheet by a universal joint, and a cap inclosing the outer end of the staybolt and secured to the outer sheet by a welded joint formed between the face of the sheet and side of the butt portion of the cap, whereby the pressure within said cap results in a tensile stress on the welded joint with substantially no bending stress.

9. The combination with an outer and inner sheet, of a stay bolt passing therethrough, said stay bolt being provided with a longitudinal opening and having an enlarged head, a non-circular recess in said head, a seat interposed between said recess and said longitudinal opening adapted to receive a plug, and a cap inclosing said head and welded to said outer sheet.

In witness whereof I hereunto subscribe my name.

ROBERT S. MENNIE.
